(57) **CLAIM**

The ornamental design for a frame for magnets in magnetic resonance imaging, as shown and described.

DESCRIPTION

FIG. 1 is a top, front, right side perspective view of a frame for magnets in magnetic resonance imaging showing the claimed design, with the top, front, left side perspective view being a mirror image thereof;

FIG. 2 is a top view thereof, with the bottom view being a mirror image thereof;

FIG. 3 is a front view thereof, with the rear view being a mirror image thereof; FIG. 4 is a left side view thereof, with the right side view being a mirror image thereof;

FIG. 5 is a top, rear, right side perspective view thereof, with the top, rear, left side perspective view being a mirror image thereof;

FIG. 6 is a bottom, front, right side perspective view thereof, with the bottom, front, left side perspective view being a mirror image thereof; and,

FIG. 7 is a bottom, rear, right side perspective view thereof, with the bottom, rear, left side perspective view being a mirror image thereof.

The broken lines in the figures show portions of the frame for magnets in magnetic resonance imaging that form no part of the claimed design.
